(57) **CLAIM**

The ornamental design for a dispenser/receptacle system, as shown and described.

DESCRIPTION

FIG. 1 is a perspective view of the dispenser/receptacle system;

FIG. 2 is a front elevational view of the dispenser/receptacle system;

FIG. 3 is a left side elevational view of the dispenser/receptacle system, the right side being a mirror image of that shown;

FIG. 4 is a rear view of the dispenser/receptacle system;

FIG. 5 is a top plan view of the dispenser unit of the dispenser/receptacle system;

FIG. 6 is a bottom plan view of the dispenser unit of the dispenser/receptacle system;

FIG. 7 is a top plan view of the receptacle unit of the dispenser/receptacle system; and,

FIG. 8 is a bottom plan view of the receptacle unit of the dispenser/receptacle system.

The broken lines most closely adjacent the periphery of views of the dispenser/receptacle represent the bounds of the claimed design while all other broken lines are directed to support and interior structure and are included for illustrative purposes only; the broken lines form no part of the claimed design.
